UNITED STATES PATENT OFFICE

MATSON C. TERRY, OF PHILADELPHIA, PENNSYLVANIA, ASSIGNOR TO WESTINGHOUSE ELECTRIC & MANUFACTURING COMPANY, A CORPORATION OF PENNSYLVANIA

REFRIGERATOR

Application filed November 19, 1925. Serial No. 70,118.

My invention relates to refrigerating machines and particularly to small capacity machines of the compression type which are suitable for household use and it has for an object to provide apparatus of the character designated which shall operate reliably and effectively for extended periods of time. It has for a further object to provide a refrigerating machine which shall embody a novel structure for condensing the refrigerant vapor and which shall have facilities for cooling the condensed refrigerant prior to its entrance into the evaporator.

These and other objects, which will be made apparent throughout the further description of my invention, may be attained by the employment of the apparatus hereinafter described and illustrated in the accompanying drawings in which Figure 1 is a view, partly in section and partly in elevation, of one form of refrigerator arranged in accordance with my invention; Figure 2 is a view, in section, taken on the line II—II of Figure 1; Figure 3 is an enlarged section taken on the line III—III of Figure 1; Figure 4 is an enlarged detailed view, in sectional elevation, of the condensing and compression mechanisms employed in the refrigerator shown in Figure 1; Figure 5 is a plan view of the condensing and compression mechanisms shown in Figure 4 and Figure 6 is a partial view, in elevation, of another form of condensing chamber which I may employ and which is similar to that shown in Figures 4 and 5 with the exception of the arrangement of the cooling fins.

The installation of the compression mechanism, that is, of the compressor and its driving motor, in a single fluid tight casing possesses numerous advantages inasmuch as a very compact arrangement is provided, the use of a stuffing box is avoided, quiet operation is insured and leakage of the refrigerant fluid is prevented. The entire arrangement of the refrigerating mechanism may be still more simplified by utilizing the enclosing casing as a condensing chamber and as air cooling is generally preferred to water cooling, the heat of condensation may be absorbed through the walls of the casing by a current

of air circulated by a blower or similar apparatus. However, the casing enclosing the compression mechanism, as ordinarily constructed, does not possess sufficient external surface to dissipate the required amount of heat and it therefore becomes necessary to augment this surface by the provision of some form of cooling fin. The process of attaching these cooling fins to the casing, if performed in the well known manner generally employed with the manufacture of various types of heat exchange apparatus, considerably complicates the structure of the casing and materially increases its manufacturing cost.

I have, therefore, conceived the idea of providing an undulated, or pleated, or fluted heat radiating member adapted to be wrapped around the casing and which is held in excellent contact therewith by a suitable jacket or shroud, the assembled structure having been immersed in a bath of molten tin for forming a single or integral structure. The heat flow from the casing to the radiating member is facilitated by the metallic bond formed between these two structures by the tin. By this means, a stamped or forged casing may be employed, thus avoiding the porosity and weight of cast casings. In addition, the jacket or shroud which retains the fins in position may be extended to form a housing for the blower employed for circulating the air, the blower being preferably superimposed upon the condensing chamber and arranged to discharge the air downwardly between the condensing chamber and the jacket.

Another feature of my machine consists of providing a cooling coil in the jacket, which cooling coil is arranged in the path of the air discharged by the blower. This cooling coil is utilized to reduce the temperature of the condensed refrigerant prior to its entrance into the evaporator whereby, after having passed through the expansion valve, the cooled condensate assumes a still lower temperature and the capacity of the machine is thus increased. Another feature of my machine consists in so arranging the condensing chamber within the machinery compart-

ment that all of the air discharged by the blower is compelled to pass over the condensing chamber.

The above features, together with numerous other features to be described hereafter, cooperate to provide a refrigerating machine well adapted for domestic installation and for effective operation under the exacting requirements of household use.

Referring to the drawings for a more detailed description of my invention, I show in Figures 1, 2 and 3 a refrigerator box 10 having an upper or cold storage compartment 11 and a lower compartment 12. In most refrigerating machines heretofore constructed, this lower compartment 12 has been completely occupied by the condensing and compression mechanisms. However, my condensing and compression mechanism are of such compact design and are composed of such few parts that they occupy only a relatively small portion of this lower compartment. Accordingly, I sub-divide this lower compartment into a small machinery compartment 13 and a relatively large storage compartment 14. The latter compartment is preferably arranged to receive dry stores and the temperature prevailing therein is the same as that of the surrounding atmosphere. An access door 15 is provided for the cold storage compartment while two access doors 16—16 are provided for the storage compartment 14. My refrigerator box is preferably so constructed that there is no access to the machinery compartment 13 from the front portion of the box. However, in the rear of the box I have provided a removable cover 17 by means of which complete access may be had to the interior of this compartment. I may also, if I desire, so arrange the division wall 18 that it may be removed from the refrigerator box after the removal of the cover 17. Located in the machinery compartment 13 is a unitary structure 21 embodying the condensing and compression mechanisms.

As shown in Figure 4, the unitary structure 21 comprises a casing 22 having disposed therein a structure 23 for supporting and housing a compressor 24 together with its driving motor 25. The compressor 24 is preferably of the rotary, two stage type. The structure 23 forms what may be termed a motor housing 26 and a lubricant receptacle 27. The compressor 24 is provided with an inlet port 28 and a discharge port 29. Located directly above the discharge port 29 is a baffle 31 which is so arranged that any liquid discharged through the port 29 is impinged thereon and deflected into the lubricant receptacle 27. Both the casing 22 and the structure 23 are secured through bolts 32 to a removable base plate 33, removal of the latter permitting inspection of the entire compression mechanism.

Surrounding the casing 22 is an undulated or ruffled heat radiating member 34 which I preferably construct in one piece and then wrap about the casing as shown in Figure 5. The member 34 is retained in excellent contact with the outer surface of the casing 22 by means of a jacket 35 which surrounds the member 34 and which is provided with end clamping means 36 adapted to compress the heat dissipating member between the casing and the jacket. The entire structure is preferably dipped in a bath of tin or some similar substance so that the casing 22, the heat radiating member 34 and the jacket 35 are formed into a single or integral structure. With such an arrangement, the undulated heat radiating member forms a plurality of substantially V shaped cooling fins which make autogenous contact with the casing as well as with the jacket so that the area of not only the V shaped fins but the jacket 35 as well is utilized to dissipate the heat. In this way, the casing 22 may be made by stamping or forging or some comparatively inexpensive process of manufacture totally disassociated from the manufacture of the cooling fins. Furthermore, the cooling fins may be assembled upon the casing in a very short time and at very little cost. By providing very efficient cooling fins, such as disclosed herein, the casing 22 may be made comparatively small.

The jacket 35 is provided with a detachable extension 37 which houses a blower 38. The blower 38 is driven by an independent motor 39 located in a housing 41 which in turn, is supported in the blower casing 37 by suitable brackets 42. The blower 38 is arranged to draw air inwardly through the upper or entrant portion 43 of the jacket and to discharge it downwardly through and between the V's formed by the heat radiating member 34. The air finally emerges from the lower or exit portion 44 of the jacket.

Provided in the base plate 33 is a refrigerant vapor inlet 45 which connects through a passage 46 with the bore of the motor shaft 47, the latter in turn being connected through a passage 48 with the inlet port 28 of the compressor. Condensed refrigerant fluid is discharged from the casing 22 through an outlet 49 provided in the base plate 33, which outlet communicates, through a conduit 51, with a cooling coil 52 arranged in the lower portion of the jacket 37.

As most household refrigerating machines operate only intermittently, it is advisable to provide a check valve between the high and low pressure portions of the machine in order to prevent rapid equalization of pressures and consequent loss of refrigeration during the idle or shut off period.

A check valve 50 is therefore provided in the conduit 51 for preventing the back flow of

condensed refrigerant fluid into the condensing chamber, as the latter normally contains no accumulation of condensate. However, the practice heretofore has been to locate this check valve in the vapor conduit connecting the outlet of the evaporator with the inlet of the compressor but I prefer to locate it in the conduit connecting the outlet of the condenser with the inlet of the evaporator for the following reasons: When the check valve is located in the evaporator conduit connecting the outlet of the evaporator with the inlet of the compressor, its operation is noisy because the slugs of liquid entrained in the refrigerant vapor exert a constant hammering action upon the movable ball or disc within the valve body. In addition, the work required to retain the ball or disc away from its seat reduces somewhat the vacuum which the compressor is capable of maintaining within the evaporator and this consequently reduces the capacity of the machine. On the other hand, where the valve is located in the condensed refrigerant, there is a constant passage of nothing but a relatively small volume of liquid and all hammering action is eliminated. Furthermore, because it is not located between the compressor and the evaporator, it does not affect the vacuum within the evaporator. It is therefore apparent that locating the check valve in the position illustrated possesses numerous advantages as it insures more effective as well as more quiet operation of the machine.

The cooling coil 52 communicates through a conduit 53, shown in Figures 1 and 2, with an evaporator 54 located in the cold storage compartment of the refrigerator box. Provided in the conduit 53 is a float valve 55 for controlling the flow of refrigerant fluid to the evaporator. Refrigerant vapor generated in the evaporator is returned by a conduit 56 to the inlet 45 of the condensing and compression mechanism.

The unitary structure 21, which embodies condensing and compression mechanisms, is preferably supported upon the bottom wall 57 of the machinery compartment 13. A rubber or felt pad 58 may be inserted between the base plate and the bottom wall in order to insulate the vibration of the compression mechanism from the refrigerator box. Air is supplied to the blower through an opening 59 provided in the upper portion of the removable plate 17 while the air is discharged from the refrigerator box through outlets 61 provided in the bottom wall 57. Suitable screening material 60 is arranged over both the inlet 59 and the outlet 61 to prevent the ingress of anything which might interfere with the successful operation of the machine. A division wall 62 is provided in the machinery compartment. This division wall engages the jacket

35 of the unitary structure 21 and compels all air discharged by its blower 38 to pass between the jacket 35 and the casing 22. The division wall 62 is preferably made in two portions so as to permit removal of the entire structure 21 from the machinery compartment. The front and rear walls of the refrigerator box are provided with downwardly extending portions 63 and 64 respectively which reach almost to the supporting structure or floor and which extend throughout the entire length of the box. These extending portions form a duct for conveying air discharged through the outlets 61 to opposite ends of the refrigerator box.

The operation of the above embodiment of my invention is as follows:

Assuming the machine to be in operation, the compressor 24 discharges through its discharge port 29 compressed refrigerant vapor. The refrigerant fluid which I prefer to employ consists of a refrigerant and a lubricant, such as ethyl chloride and mineral oil, which together form a physical solution and which is disclosed in a co-pending application of A. A. Kucher's serially numbered 617,844, filed February 8, 1923 and entitled Working fluid for refrigeration. Any liquid entrained in the evaporator discharged by the compressor is separated therefrom by the baffle 31 and falls into the lubricant receptacle 27 after which it is utilized to lubricate the working parts of the machine.

The refrigerant vapor completely fills the casing 22 and heat is absorbed therefrom through the constant passage of air downwardly between the jacket 35 and the casing 22. The condensed refrigerant thus formed is conveyed by the conduit 51 to the cooling coil 52 and a large portion of the sensible heat of this liquid is abstracted in its passage through the coil by the circulating air. In this way, the refrigerant liquid is cooled so that after passing through the float valve 55 into the evaporator, or region of relatively low pressure, expansion causes it to assume an extraordinarily low temperature.

Heat is abstracted from the cold storage compartment of the refrigerator box in a manner well understood in the art and the vapor generated within the evaporator by this heat absorption process is returned by the conduit 56 to the inlet 45 of the compression mechanism, whereupon the cycle of operation is repeated.

The blower 38 draws the air required for condensing purposes inwardly through the opening 59 provided in the rear wall of the refrigerator box. This air is then discharged downwardly over the cooling coil 52 and is discharged at the lower end 44 of the jacket 35 to the outlets 61 provided in the bottom wall of the box. This relatively warm air is then prevented from flowing up along the front or rear walls of the box and entering

either the cold storage compartment or the air inlet 59 by the downwardly extending members 63 and 64. The latter form a duct which compels this warm air to pass outwardly to the ends of the box. In addition, because of the dividing wall 62, all air discharged by the blower is compelled to pass between the casing 22 and the jacket 35 as this is the only means of communication provided 5 between the air inlet portion of the machinery compartment and the air outlet portion. In this manner very effective cooling and adequate condensation of the refrigerant fluid is effected with a minimum amount of heat 10 radiating surface.

In Figure 6 I have shown still another form of condensing chamber which consists of the casing 22 and the jacket 35 as heretofore described. However, each cooling fin 20 is undulated and is made separately, the respective cooling fins being held in contact with the casing 22. By shaping the cooling fins in this manner, additional heat radiating surface is obtained over that derived by 25 employing straight fins and consequently the condensing chamber may be made proportionately smaller. Furthermore in passing through the spaces between these fluted fins, the air becomes turbulent and gives up its 30 heat more readily.

While I have shown my invention in but two forms, it will be obvious to those skilled in the art that it is not so limited, but is susceptible of various other changes and modifications, without departing from the spirit thereof, and I desire, therefore that only such limitations shall be placed thereupon as are imposed by the prior art or as are specifically set forth in the appended claims.

What I claim is:—

1. In a refrigerating apparatus, the combination of an evaporator, a condenser, a fluid-tight casing enclosing a motor and a compressor, substantially V shaped cooling fins provided upon the outer walls of the casing, a jacket surrounding the cooling fins, and a blower for passing air between the casing and the jacket.

2. In a refrigerating apparatus, the combination of an evaporator, a condenser, a fluid-tight casing enclosing a compression mechanism, substantially V shaped cooling fins provided upon the casing, and a blower disposed at a higher elevation than the casing 55 for passing air thereover.

3. In a refrigerating apparatus, the combination of an evaporator, a fluid-tight casing forming a condensing chamber, a compression mechanism disposed within the casing, substantially V shaped cooling fins provided upon the casing, a jacket surrounding the cooling fins, and a blower superimposed upon the casing for circulating air between the casing and the jacket.

4. In a refrigerating apparatus, the com-

bination of a compression mechanism, a closed casing forming a condensing chamber, a jacket surrounding the casing, a blower for circulating air between the casing and the jacket, a cooling coil located in the jacket, means for conveying condensed refrigerant fluid from the casing to the cooling coil, an evaporator, and means for conveying the cooled condensed refrigerant fluid from the cooling coil to the evaporator.

5. In a refrigerating apparatus, the combination of a refrigerator box having a cold storage compartment and a machinery compartment, an evaporator disposed in the cold storage compartment, a compression mechanism and a condenser disposed in the machinery compartment, said condenser having a surrounding jacket for conveying air, an air inlet provided in one portion of the machinery compartment and an air outlet provided in another portion of the machinery compartment, a blower associated with the condenser for creating a current of air from the inlet through the jacket to the outlet, and a division wall engaging the jacket and sub-dividing the machinery compartment into an air inlet compartment and an air outlet compartment, whereby all of the air passing from the inlet to the outlet is compelled to pass through the condenser jacket.

6. In a refrigerating apparatus, the combination of a refrigerator box having its bottom wall spaced from its supporting structure, an upper cold storage compartment and a lower machinery compartment provided in the box, an evaporator provided in the cold storage compartment, compression and condensing mechanisms disposed in the machinery compartment, an air inlet for the machinery compartment provided in one of the vertical walls of the box, an air outlet for the machinery compartment provided in the bottom wall of the box, and a baffle formed by a downward extension of the rear wall of the box which contains the air inlet, whereby the heated air discharged by the outlet in the bottom wall of the box is prevented from traveling upwardly along that vertical wall of the box which contains the air inlet.

7. In a refrigerating apparatus, the combination of a refrigerator box having its bottom wall spaced from its supporting structure, an upper cold storage compartment and a lower machinery compartment provided in the box, an evaporator provided in the cold storage compartment, a compression mechanism and a condenser disposed in the machinery compartment, an air inlet for the machinery compartment provided in one of the vertical walls of the box, an air outlet for the machinery compartment provided in the bottom wall of the box, and a duct formed by downward extensions of the front and rear walls of the box for conveying the discharged air to the sides of the box.

8. Refrigerating apparatus comprising an evaporator, and a heat-dissipating unit including a compressor and a driving motor therefor, a fluid-tight casing enclosing the motor and compressor, and means for radiating heat from said casing, said means comprising an annulus of fins surrounding the casing and maintained in heat-conducting relation with the casing by a clamping means encircling the outer edges of the fins.
9. Refrigerating apparatus comprising an evaporator, and a heat-dissipating unit including a compressor and a driving motor therefor, a fluid-tight casing enclosing the motor and compressor, and means for radiating heat from said casing, said means comprising an annulus of fins of zig-zag formation surrounding the casing and maintained in heat-conducting relation with the casing by a clamping means encircling the outer edges of the fins.

In testimony whereof, I have hereunto subscribed my name this sixteenth day of November, 1925.

MATSON C. TERRY.

8. Refrigerating apparatus comprising an evaporator, and a heat-dissipating unit including a compressor and a driving motor therefor, a fluid-tight casing enclosing the motor and compressor, and means for radiating heat from said casing, said means comprising an annulus of fins surrounding the casing and maintained in heat-conducting relation with the casing by a clamping means encircling the outer edges of the fins.

9. Refrigerating apparatus comprising an evaporator, and a heat-dissipating unit including a compressor and a driving motor therefor, a fluid-tight casing enclosing the motor and compressor, and means for radiating heat from said casing, said means comprising an annulus of fins of zig-zag formation surrounding the casing and maintained in heat-conducting relation with the casing by a clamping means encircling the outer edges of the fins.

In testimony whereof, I have hereunto subscribed my name this sixteenth day of November, 1925.
